UNITED STATES PATENT OFFICE.

EDWIN BALL, OF BIRMINGHAM, AND CLARENCE E. ABBOTT, OF BESSEMER, ALABAMA.

METHOD OF MINING.

Application filed May 12, 1922. Serial No. 560,394.

To all whom it may concern:

Be it known that we, EDWIN BALL and CLARENCE E. ABBOTT, citizens of the United States, and residents of Birmingham, Alabama, and Bessemer, Alabama, respectively, have invented certain new and useful Improvements in Method of Mining, of which the following is a specification.

Our invention relates to mining methods and more particularly to the method of mining iron ore or other material lying in seams or in a more or less uniform deposit on an incline plane.

One object of the invention is to provide a novel method or a combination of mining operations whereby the development and exploration work may be pursued and at the same time the mine may be worked to its maximum capacity and the cost of mining lessened.

Another object of the invention is to provide a novel method of mining whereby the mine is efficiently ventilated, the safety of the employees obtained and damage to the mine is overcome and prevented.

Another object of the invention is to provide an improved method of mining in which the blasting, loading and handling operations are facilitated and wherein the ore or material is removed with increased rapidity, thereby lessening the operating costs and increasing the capacity of the mine.

Other objects of the invention will be apparent from the following specification when read in connection with the accompanying drawings in which—

Fig. 1 is a plan view showing the preferred manner of forming the mine and removing the ore or material in accordance with our invention;

Fig. 2 is an enlarged view of a part of the mine shown in Fig. 1, illustrating more specifically the method of removing the ore and the haulage operations;

Fig. 3 is a perspective view of a stope illustrating the drilling and blasting operation;

Fig. 4 is a longitudinal section on line 4—4 of Fig. 1;

Fig. 5 is a cross-section on line 5—5 of Fig. 1;

Fig. 6 is a plan view of a stope similar to Fig. 3 illustrating the operation of removing broken ore from a stope by means of one type of mechanical ore loader;

Fig. 7 is a section on line 7—7 of Fig. 6.

Referring to the drawings 3 designates a longitudinal slope or main haulway tunnel which is driven from the surface beneath the ore seam or deposit for a sufficient distance in the initial stage of the mining operation. A plurality of lateral levels 4, 6, 8, 10 and 5, 7, 9 and 11 are turned off on opposite sides in the ore or other material to be mined. The lateral levels intersect the main slope 3 (shown in Figs. 4 and 5) at locations elevated from the floor of said slope so as to facilitate the dumping of ore from the tram cars in said levels into the skip which traverses the main haulway slope. After the slope or main haulway tunnel 3 has been projected a sufficient distance, manways 12 and 13 are driven in the deposit paralleling the slope on opposite sides thereof and leaving sufficient bodies of ore or material standing between the slope and manways to insure safety. These manways are then driven to the surface, the lateral levels are continued and the manways driven in advance or ahead of the slope on both sides of the projected center line thereof. At intervals advance levels 16 and 17 are driven across the slope center line from one manway to the other and the slope 18—19 excavated or raised from the lower to the next higher level. New lateral levels 20 and 21 are then turned off the manways 12 and 13 at the level 16 and the manway pushed forward as at 22 and 23, new levels 24 being driven across between the manways and the slope 19 raised and connected, new lateral levels 20 and 21 are continually turned off the manways as the development work proceeds.

The advantages of this system of development are, that the manways being driven in the ore or material, any change in grade occasioned by faults, dips or other causes may be rectified with a minimum of expense, and by raising the slope from the advance levels the construction of bulkheads or pentices, for the protection of the workmen against accidents on the main haulway, is made unnecessary. Also the disadvantage of water flowing down into the face while driving the slope is eliminated.

After a number of lateral levels such as 4, 5, 10, 11, 29, 30 and so forth have been driven a sufficient distance from the manways 12, 13 to leave protecting pillars 14, 15, upsets or raises 40, 42, 43, 45, 47 are driven

through at intervals to the level above and stoping is begun as at 44, 46, 49 and 51. The size or area of the stopes are determined by the condition of the roof, the amount of material necessary to be left to form the pillars such as 52, 52^a, 52^b, 54, 55, 55^a, 55^b, 56, 56^a, 56^b, 57, 57^a, 57^b, 58, 59 to insure safety in working the mine, and by the location of the pillars in the adjacent stopes above and below. The stoping is preferably done in such manner that the large pillars are left staggered or one pillar such as 53 in line with similar pillars 55 or 61 two stopes above or below. Small pillars 52^a and 52^b are left in the center or at other locations in the stope where conditions make them necessary or advisable. This arrangement gives the greatest possible protection for economically and safely mining the ore or other material.

After the upsets 40, 42, 43 and 45 and so forth have broken into the level above, underhand stoping at 44, 46, 49 and 51 is commenced on one side of each stope as the pillars 56, 60, 63 and 65 form one side of each of the upsets.

Referring to Figs. 3 and 6, drilling is begun at the top of the stope 65^a and the holes drilled at an angle as indicated by dotted lines at 70 and 71 to a depth that will break down the maximum amount of material with a minimum charge of explosive.

After one round of blasting, a step or bench such as 66 is left. The next round is drilled at a regular interval below at substantially the same angle and depth then blasted. This is continued down the stope leaving a regular series of steps or benches 66, 67, 68 and 69 which are drilled and blasted in turn until the limit of the stope is reached, then the stope is squared up along a line substantially parallel to the main slope 3. By the use of this method the ribs or sides of the stope are worked in a line substantially parallel to the main haulway slope and at right angles to the tracks in the lateral levels, thus facilitating the operation of the various types of drag line or other mechanical ore loaders, enabling them to easily reach any part of the stope.

Figs. 2, 6 and 7 illustrate a type of drag line mechanical ore loader adapted to be used in connection with our improved method of mining. The winding apparatus of this type of loader is placed on the tracks 70, 71, 72 and 73 in the levels and sheave blocks 74 are attached to timbers 75 or to the rib or footwall, to guide the drag cables 76 and 77. One end of the cable 76 is wound on and secured to a winding drum 78 carried by a car 79, the other end of said cable being attached to the front end of a drag scraper 80 and serving as an inhaul cable. The other cable 77 is wound on a second drum 81 and passes through one or more

guide sheave blocks 74 and is attached to the rear of the drag scraper 80, serving as an outhaul cable.

In operation, the inhaul cable 76 on one drum 78 is wound in, pulling the scraper forward in a straight line, through a chute 82 and dumping into a car 83 on the tracks in the level, the drum 81 running loose during this operation. After the scraper has discharged its load, the inhaul drum is disconnected from its drive by throwing a suitable clutch and the drum 81 is connected and the outhaul cable wound in returning the scraper for another load.

This arrangement may be used as shown in Fig. 2 in upsets or raises as at 47, in stopes as at 49, in the face of a level as at 21^a and also at an angle as shown in the stope 90 where the scraper works around the small pillars 55^b thus efficiently and economically removing the broken ore to cars in the levels.

The tracks 70, 71, 72, 73 and so forth in each level are laid from the tipplers 94, 94^a, 95, 95^a, 96, 96^a, 97 and 97^a at the main slope toward the face. These tracks are of the usual mine construction and are laid so that the grade increases toward the face as it is driven back from the main slope 3 to facilitate tramping, as in many cases the loaded cars may be trammed down by gravity. In such cases either animal or mechanical haulage will be necessary to return the empty cars to the working places. The levels may be double tracked as shown in the level 72 and also a third track may be placed as shown in this level thus allowing a number of cars to await their turn to be dumped into the main haulage skip, or cars may be transferred from one level to another. By this arrangement two cars may be dumped at the same time and the empty cars switched aside until all loaded cars have been dumped, without waiting to return the empty cars to the working places.

The levels may be double tracked at the working places as shown in Fig. 2 in order to facilitate the operation of a mechanical ore loader or if necessary, three tracks may be installed and also a storage track for empty cars may be placed in the level near the working place to eliminate the delay in waiting on empty cars. However, in our improved method we do not limit ourselves to any particular haulage system or type of underground tipple.

An advantage in the use of our method of mining, which will be apparent to those skilled in the art, is the elimination of a commonly used system of driving levels at intervals from the main haulways and at intervals driving upsets connecting the levels and leaving narrow, horizontal pillars between the levels. Such a system necessitates much costly narrow work in continually driving the face, a high explosive cost in

driving the same and permits of a very limited working face, necessitating a much greater number of working levels than required by our system, as well as greatly limiting the economical use of the various types of mechanical ore loaders in handling the broken material. In mining according to our improved method the narrow work, with its high cost of blasting and handling is confined to driving past pillars, as the maximum amount of material may be broken with a minimum amount of explosives and a much larger working face may be obtained in the stopes, enabling a considerable output from comparatively few working levels, thereby reducing the cost of haulage and greatly facilitating the economical use of mechanical ore loaders.

What we claim is:

20 1. The method of mining which consists in driving a main slope beneath an inclined seam or deposit, turning levels laterally from the slope in the deposit, driving manways in advance of the main slope and substantially parallel to the center line thereof, connecting the manways by levels in advance of the slope and raising the slope from said levels.

25 2. The method of mining which consists in driving a main slope, turning lateral levels from the slope, driving manways in advance of and on opposite sides of the slope center line projected, connecting the manways by lateral levels below the forward end of the main slope and excavating the slope from said levels.

30 3. The method of mining which consists in driving a main slope beneath an inclined seam or deposit, turning levels laterally from the slope in the deposit, driving manways in advance of the main slope and substantially parallel to the center line thereof, connecting the manways by levels, continuing the slope from said levels and driving said levels laterally from the manways.

35 4. The method of mining which consists in driving a plurality of levels at different elevations from a main slope, raising inclined upsets from the lower to the higher levels, stoping from the upsets to leave large staggered pillars with smaller pillars between them.

40 5. The method of mining which consists in driving a main slope, turning lateral levels from the slope, driving manways in advance of and on opposite sides of the slope center line projected, connecting the manways by lateral levels raising the slope from the last named levels, raising upsets from

other levels and stoping from said upsets so that the mining operations can proceed without interfering with the development or exploration work.

5 6. The method of mining which consists in driving a plurality of levels through the deposit, raising upsets at approximately equal intervals from one level to the adjacent higher level, the upsets in the several levels throughout the mine being formed approximately in line and the stoping being carried on so as to leave large pillars standing in staggered relationship with one another in adjacent levels.

65 7. The method of mining which consists in driving a main slope below the deposit, driving a plurality of lateral levels through the deposit, raising upsets from the lower to the higher levels, and stoping by drilling and blasting successive benches from said upsets substantially parallel to said main slope and mechanically conveying the ore thus mined to tram cars in said levels.

70 8. The method of mining which consists in driving a main slope below the deposit, driving a plurality of lateral levels through the deposit, raising inclined upsets from the lower to the higher levels, drilling and blasting a series of successive benches, substantially parallel to said main slope in said upsets to form inclined stopes from which the ore can be readily removed, scraping the ore along the inclined stopes to tram cars in said levels and dumping the ore from said tram cars into a skip which traverses the main slope.

75 9. The method of mining which consists in driving a main slope, turning levels laterally from the slope, driving a manway in advance of the main slope substantially parallel to the projected center line thereof, driving lateral levels from said manway in advance of and below the main slope and raising the slope from the lower levels.

80 10. The method of mining which consists in driving a main slope beneath an inclined seam or deposit, turning levels from said main slope in the deposit, driving a manway in advance of the main slope in the general direction thereof turning a lateral level from said manway in advance of the main slope and connecting the slope from said advance lateral level.

In witness whereof, we have hereunto signed our names.

EDWIN BALL.
CLARENCE E. ABBOTT.
